D. F. CURTIN

POCKET PENCIL HOLDER

Filed Jan. 22, 1925

Patented May 18, 1926.

1,585,235

UNITED STATES PATENT OFFICE.

DAVID FRANCIS CURTIN, OF CHICAGO, ILLINOIS.

POCKET PENCIL HOLDER.

Application filed January 22, 1925. Serial No. 3,916.

This invention relates to improvements in a pocket pencil holder similar to that described and claimed in my Patent No. 1,500,375, for "pocket pencil holder", dated July 8, 1924; and embracing a compact device wherein a pair of telescoping members are actuated by enclosed resilient means.

It is an object of this invention to provide a pocket pencil holder of a spring enclosed type adapted, when disposed within a pocket, to hold pens, pencils and other articles in place.

It is a further object of this invention to provide a pocket pencil holder wherein telescoping toothed members containing an enclosed spring are adapted to be placed between the walls of a pocket to tension said walls to cause the same to act as retaining means for holding pencils, pens, and other articles in the pocket against accidental removal.

It is furthermore an object of this invention to eliminate the inconvenience caused by an external spring in the pocket forming an obstruction to the insertion and removal of articles, by substituting therefor an enclosed spring, thus making the articles of invention both more useful and neater in appearance.

It is an important object of this invention to provide a simple, improved pencil holder of compact form adapted to be cheaply produced and eliminating the use of external parts which might cause obstructions to articles when being placed in a pocket to be held in place by the improved holder.

Other and further important objects of the invention will be apparent from the disclosures in the specification and the accompanying drawings.

The invention (in a preferred form), is illustrated in the drawings and hereinafter more fully described.

On the drawings:

Figure 1 is a fragmentary elevation of a garment having a pocket provided with a pocket holder embodying the principles of this invention.

Figure 2 is an enlarged sectional view taken on line II-II of Figure 1.

Figure 3 is a front elevation of the device embodying this invention in a preferred form removed from the pocket, showing the operation in dotted lines.

Figure 4 is an enlarged longitudinal section of the device with parts in elevation.

Figure 5 is an enlarged transverse detail section on the line V-V of Figure 3.

Figure 6 is an enlarged longitudinal detail section taken on line VI-VI of Figure 60 3.

Figure 7 is a front elevation of a modified form of the device.

Figure 8 is an enlarged longitudinal section of the device shown in Figure 7 with parts in elevation.

Figure 9 is an enlarged transverse detail section taken on the line IX-IX of Figure 7.

Figure 10 is a front elevation of another modified form of the device.

Figure 11 is an enlarged transverse detail section taken on the line XI-XI of Figure 10.

As shown on the drawings:

The reference numeral 1 indicates a portion of a vest or coat provided with a pocket 2 having disposed therein a notebook 3 and a pencil 4 placed on opposite sides of an improved article holder.

The improved article retainer and pocket extender is of simple and inexpensive construction, embracing a flattened metal sleeve 5, one outer end 6 of which is closed by the abutment of two flanges on said end, 85

and struck-off teeth 7, one or more from each flange. Slidably engaged in the open end of sleeve 5 is a metal bar 8, the outer end of which is provided with teeth or projections 9. A flat, ribbon spring 10 is enclosed within the sleeve, secured at one end by the pin 11, the other end abutting the inner end of the metal bar 8. The spring 10 acts to normally slide the telescoping members 5 and 8 outwardly with respect to one another so that the toothed ends of said members will be forced against the side seams of the pocket 2 when the device is inserted into the mouth of the pocket 2 and the telescoped members are released. The 100 spring 10 thus acts to hold the telescoped members extended to tension the mouth of the pocket to hold the pencil 4 and the hook 3 within the pocket and against the sides of the holder or extender device. The pencil holder thus serves as a means for holding

articles such as pencils, fountain pens and the like in proper position within a pocket between the telescoping members and the tensioned pocket walls.

In the form of device illustrated in Figures 1 to 6 inclusive the metal bar 8 has a

longitudinal slot 12 through which extends lugs 13 turned up from the end of the sleeve 5 to limit the expansion of the two telescoping members 5 and 8.

5 Figures 7, 8 and 9 show a device similar to that shown in Figures 1 to 6 inclusive, with the exception that the lugs 13 are replaced by a pin 14 secured transversely in the sleeve 5 and passing through the slot 12 10 in the bar 8.

A second modified form of the device is shown in Figures 10 and 11 in which the sleeve is slotted instead of the bar, and the limiting means is on the bar instead of the 15 sleeve. The sleeve 5 has a slot 15 through which a stop pin or lug 16 turned up from the inner end of the bar 8 protrudes.

These modifications all act in substantially the same way and illustrate some of the 20 different means by which the two telescopic members may be prevented from moving out of coacting engagement by the action of the control spring 10.

I am aware that many changes may be 25 made, and numerous details of construction may be varied through a wide range without departing from the principles of this invention, and I therefore do not purpose limiting the patent granted hereon, otherwise 30 than necessitated by the prior art.

I claim as my invention:

1. A pocket pencil holder comprising a 35 sleeve closed at one end, teeth formed on said end, a slotted bar slidably engaged in said sleeve having teeth on its outer end, an enclosed spring secured near the closed end of said sleeve and contacting the inner end of said bar, and means on said sleeve having sliding engagement with said slot

for limiting the relative movements of said 40 sleeve and bar.

2. A pocket pencil holder comprising a tubular member closed at one end, teeth formed on the closed end of said member, a solid member slidably projecting into the 45 open end of said tubular member, teeth on the outer end of said solid member, an enclosed spring having one end thereof secured to said tubular member and the other end abutting said solid member, one of said 50 members having a slot and the other having a lug cooperating therewith for limiting the relative movements of said members.

3. A pocket pencil holder comprising a sleeve, abutting flanges closing one end of 55 said sleeve, a tooth on each of said flanges, a bar slidably engaged in the open end of said sleeve and having a slot therein, teeth on the outer end of said bar, a spring disposed within said sleeve, one end of said 60 spring secured to said sleeve, the other end of said spring abutting the inner end of said bar, and lugs turned up from the open end of said sleeve passing through said slot to limit the relative movement of said sleeve 65 and said bar.

4. In a pocket pencil holder of the class described, a pair of telescoping toothed members, one of said members having a slot 70 therein, means on the other member projecting into said slot to limit the relative movement of said members, and resilient means in one of said members abutting the other of said members for holding said members in extended position. 75

In testimony whereof I have hereunto subscribed my name.

DAVID FRANCIS CURTIN.
